INVENTOR
Theodor R. Willwerscheid

BY *H. Johnson*
ATTORNEY

UNITED STATES PATENT OFFICE

THEODOR R. WILLWERSCHEID, OF CLEVELAND, OHIO

SIGN

Application filed August 26, 1929. Serial No. 388,425.

My invention relates to improvements in that type of sign wherein the letters or characters of the sign are spelled out by a plurality of reflecting glass buttons. As this type of sign is ordinarily constructed, the glass buttons are held within a housing with a reflecting portion of the housing back of the button, and the back plate of the sign supports a plurality of holders into which the 10 housings holding the buttons are fitted, with the buttons projecting through openings in the front plate of the sign, to form the letters or characters upon the face of the front plate.

My invention consists of new, improved means for supporting the button in the front plate of the sign, eliminating the holders ordinarily carried by the back plate.

The above and other features of my invention will be more specifically pointed out in the following description and the accompanying drawing, wherein:

Figure 1 is a plan view of a portion of the front plate of a sign fitted with my invention.

Figure 2 is a sectional view on line 2—2 of Figure 1, showing one step in placing the parts together.

Figure 3 is a sectional view on line 3—3 of Figure 2, with the parts placed together, but before the button housing is clamped in fixed position; and

Figure 4 is a view in side elevation of the button and holder, with buttons shown in finally clamped position.

Referring to the drawing in detail, A represents the front plate of a sign ordinarily made of metal. In this plate are formed openings to receive a reflecting button. The front plate, in use, will have a plurality of these openings to spell out the letters or characters constituting the sign, and the sign itself may be of any desired construction, as the ordinary highway sign, etc. The supporting mechanism for the reflecting button, constituting the essence of this invention, the

general sign construction is not, therefore, specifically shown.

In carrying out my invention, I provide a split ring 2 of suitable spring metal. This ring is formed with a flanged outer edge 3 and with the walls of the ring outwardly flaring below the flange to constitute an intermediate groove 4. Thus, by compressing the ring I am enabled to pass it through the opening 5 in the plate, then, allowing the ring to spring outwardly, to interlock with the plate, as shown in the drawing. The reflecting button may be of the construction shown in the drawing, or any desired construction.

In the form shown, a reflecting button in the form of a glass ball 6 is held within a housing 7, the upper edge of the housing 7 being clamped over the button above its medial line to hold the button within the housing. The inner wall of the bottom of the housing 8 acts as a reflecting surface to reflect the rays of light passing through the button. The bottom portion of the housing, in the form shown, is bent to form shoulders 9.

In placing the parts together, the button and housing are shoved upwardly into the ring 2 in the position shown in Figure 3, with a portion of the glass button projecting 75 beyond the sign plate. The bottom of the ring is then bent inwardly over the bottom of the housing or shoulders 9 as shown in Figure 4, to hold the button locked in position. It will be understood, that in order 80 that the button may not be pushed through the opening, the ring, where it engages the plate, must be slightly smaller than the central diameter of the button, and, that the ring itself below the opening must either flare out 85 or be otherwise large enough in diameter to receive the button.

While I have shown a standard form of reflecting button, any desired form of reflecting button may be used, as a glass ball with- 90

out an enclosing housing and with some other form of reflecting back than the particular form of housing shown in the drawing, or a cylinder with a curved face, or any other 5 form of reflecting button.

The object of my invention is to provide means, as the ring shown, arranged in connection with an opening in the plate, to entirely form a support for the button upon 10 the front plate, eliminating the use of any means upon a back sign plate for holding the button in position. In the ordinary construction, clips or holders are welded upon a back plate, and the button with its housing is 15 snapped into these clips or holders, and the front plate placed over these buttons, with the buttons projecting through the corresponding openings in the front plate. This necessitates a very accurate alinement be- 20 tween the clips or holders upon the back plate, and the openings in the front plate, so that any variation in the aligning position between the clips and openings of the front plate prevents the button being centered with 25 respect to the openings.

This difficulty in sign construction is entirely obviated in my construction, the buttons being entirely supported by the front plate.

30 While I have shown in the drawing a split ring or ferrule constructed to expand into a gripping position in the opening in the front plate, I do not restrict myself to this particular construction, but may modify the particular construction shown without departing from the ideas of my invention as embodied in the accompanying claims.

I claim:

40 1. In a reflecting device, in combination with a supporting plate formed with an opening, a reflecting button, an enclosing ferrule for said button, means for holding said button from forward movement through said ferrule, consisting of an inturned portion of

45 said ferrule projecting into anchoring engagement with said button, and means for anchoring said ferrule within the opening in said plate, said anchoring means engaging with the outer and inner faces of said plate.

50 2. In a reflecting device, in combination with a front plate formed with an opening, means for supporting a reflecting button within said opening, consisting of a ferrule, said ferrule being bent inwardly to circum-

55 ferentially overlap a portion of said button in order to keep it from passing through the ferrule, a flange carried by said ferrule overlapping the exterior face of said plate, and means carried by said ferrule engaging with

60 the inner face of said plate in opposition to the flange engaging the outer face of the plate and for the purpose set forth.

65 3. A reflecting device, comprising in combination with a front plate formed with an opening, means for supporting a reflecting

button within said opening, consisting of a ferrule portion embodying means for physical engagement with the button to clamp the button within the ferrule, and means removable without permanent deformation asso- 70 ciated with said ferrule portion for engage- 75 ment with opposite sides of the front plate adjacent the opening in said plate to hold said ferrule portion clamped within the open- 75 ing in said plate, for the purpose set forth.

In testimony whereof I affix my signature.
THEODOR R. WILLWERSCHEID.
